UNITED STATES PATENT OFFICE.

WUI KONG UN, OF HONGKONG, KWANG TUNG, CHINA.

HAT PROTECTOR.

1,402,550.

Specification of Letters Patent.

Patented Jan. 3, 1922.

Application filed January 9, 1920. Serial No. 350,401.

To all whom it may concern:

Be it known that I, WUI KONG UN, a citizen of the Republic of China, residing at Hongkong, in the Province of Kwang Tung, 5 China, have invented certain new and useful Improvements in Hat Protectors, of which the following is a specification.

The invention has for an object to effect improvements in that type of hat coverings 10 which are intended to be engaged over the hat while being worn, to protect it from being soiled by rain water or snow, or dust, whereby their manufacture will be simplified, the devices improved in certain structural details.

Additional objects, advantages and features of invention will appear from the construction, arrangement and combination of parts hereinafter described and shown in 20 the drawings, wherein,

Figure 1 is a representation of a hat in use and covered with one form of my application,

Fig. 2 is a similar view showing a hat of 25 different form,

Fig. 3 is a detail of the string guide construction,

Fig. 4 is a fragmentary bottom view of the 30 form of covering used upon the hat shown in Fig. 2.

Fig. 5 is a detail cross sectional view of the string guide device in one form,

Fig. 5^a is a similar view of a different arrangement of the string guide,

Fig. 6 is a further form of the covering.

There is illustrated in Figure 1 a turban style of hat 10, upon the head 11 of a wearer and having a covering 12 which in 40 the present instance comprises a circular blank or sheet of a transparent material, such as oiled silk, though a light material of any desirable kind may be used.

In producing the device for use with hats such as shown in Fig. 2, the sheet 12 is made 45 of such size that it will project sufficiently beyond the brim of the hat to permit it to be gathered in under the brim and close to the head of the wearer. A band 17 may be applied upon the sheet 12 around the intermediate portion of the device after it has 50 been gathered into the form shown in Fig. 6, forming a dome shaped crown covering part 18 of a size to fit loosely over the crown portion of the hat. If found preferable, a fine 55 cord or other thread 19 may be applied, as indicated in Fig. 2, which may be perma-

nently attached to the sheet in order to hold the crown portion in form, as this facilitates the rapid adjustment of the device upon the hat.

Preferably, in order to facilitate the use 60 of a gathering string or lace at the edge portion of the hat where it is drawn in beneath the hat, I provide a portion of tubing 20, which may be formed of rubber, preferably, or similar material which will tend to hold an open shape, whereby the gathering string will not become bound therein. In the attachment of rubber tubing to the 65 hat, a portion of fine rubber tubing is fixed 70 to the extreme edge portion of the sheet 12 by having one side of the tubing pinched and laid flat against the edge of the sheet, after which the flattened portion of the tube and the sheet are stitched together. In the for- 75 mation of the device for use upon turban hats the pinched portion of the tube is laid toward the outer edge of the sheet 12, whereas in the preparation of the device for use upon brim hats, the pinched portion is di- 80 rected toward the inner part of the sheet 12 while the open and enlarged part of the tube lies just without the edge of the sheet.

In the first mentioned method of attachment of the tube, the enlarged part lies 85 toward the inner part of the sheet 12 so that it will pass beneath the brim or lower edge 22 of the hat, and will present a smooth non-irritating surface toward the forehead of the wearer. In case it is desired for the device 90 to engage directly against the head of the wearer when used with hats such as shown in Fig. 2, the method of attachment of the tubing in that instance will also insure the wearer against irritation by uneven edges. 95 An important purpose in this arrangement of the tubing, however, is in order that when the draw-string is tightened it will bear against the tubing at a rounded part, and not in the convergent surfaces toward the 100 point of attachment of the tube to the hat cover, thereby assuring free movement of the string at all times and preventing uneven gathering of the cover in the main.

It is to be understood that the protector 105 can be applied to various kinds and styles of headwear beside those illustrated.

What is claimed is:

1. A device of the character described comprising a circular blank of fabric, a 110 rubber or like tube element extending around the blank having one side pinched and flat-

tened against the edge portion of the blank and fixed thereto, and a draw-string slidable in the tubular element and having end portions extended therefrom for manipulation.

- 5 2. A hat covering comprising a fabric material constructed to cover a hat and reach inwardly thereunder, a tube of cushion material having one side pinched and flattened and the flattened part secured against the
- 10 edge portion of said fabric, the open loop portion of the tube being presented in a di-

rection to lie adjacent the head of the wearer when in use, and a draw-string in the tubular element having exposed ends for manipulation. 15

In testimony whereof I have affixed my signature in presence of two witnesses.

WUI KONG UN.
